UNITED STATES PATENT OFFICE.

HENRY BRONSTHER, OF BROOKLYN, NEW YORK.

DESIGN FOR A BEVERAGE-SET STAND.

Application filed November 10, 1926. Serial No. 19,663. Term of patent 3½ years.

To all whom it may concern:

Be it known that I, HENRY BRONSTHER, a citizen of the United States, residing in the borough of Brooklyn, county of Kings, city and State of New York, have invented a new, original, and ornamental Design for Beverage-Set Stand, of which the following is a specification, reference being had to the accompanying drawing, forming part thereof.

I claim:

The ornamental design for a beverage-set stand, as shown.

HENRY BRONSTHER.
